his Atty.

UNITED STATES PATENT OFFICE.

AXEL WARNER, OF CHICAGO, ILLINOIS.

BURNER.

Application filed November 2, 1923. Serial No. 672,255.

To all whom it may concern:

Be it known that I, AXEL WARNER, a citizen of the United States, and a resident of Chicago, Cook County, and State of Illinois, 5 have invented certain new and useful Improvements in Burners, of which the following is declared to be a full, clear, and exact description.

This invention relates to burners, and in 10 its present form has been designed for use as a kerosene burner. The principal object of this invention is to provide a burner of improved construction, capable of producing an intensely hot, blue flame, and at the 15 same time eliminating the usual noise or roaring sound that accompanies the burning of kerosene in a hydro-carbon burner.

With these and other objects in view, this 20 invention consists in the several novel features hereinafter described and claimed.

The invention is clearly illustrated in the accompanying drawing, in which:—

Fig. 1 is a central, vertical section through 25 a burner embodying a simple form of the present invention; Fig. 2 is a plan thereof; Fig. 3 is a view looking at the bottom of a spreader plate forming part of the burner, and Fig. 4 is a side elevation of said plate.

Referring to said drawing, which illustrates 30 one embodiment of the invention, the reference character 5, designates a burner tube arranged to be connected to a fuel supply pipe 6, as for instance by a pipe coupling 7. The pipe 6 leads from a fuel tank 35 (not shown) in which is contained kerosene or other hydro-carbon liquid fuel, under pressure, as is well understood.

The burner tube 5 has a relatively thin 40 cylindrical shell or wall 8, which is shouldered near its upper end, as at 9 and tapers upwardly as shown at 10. The end wall 11 of the burner tube is relatively thick as compared with the shell portion 8 and contains a central discharge duct 11^a of exceedingly 45 small diameter, preferably formed by boring a hole with a fine drill. As illustrative of the size of the orifice, one having a diameter of twelve-thousandths of an inch, has been found to operate successfully. A wire gauge filter 50 30, is preferably contained in the hollow of the burner tube to filter out any solid or foreign matter from the kerosene.

Secured upon the upper end of the burner tube, and spaced therefrom, is a burner pan 55 12, which is formed with bottom 13 having an upturned marginal flange 14. The up-

per face 13^a of the bottom 13 is flat and smooth, and a central opening 15 is formed in said bottom through which the generated gas passes. The pan 12 is formed with two 60 downwardly converging arms 16, which join with a ring or band 17 that slips upon the tapered upper end 10 of the burner tube 5 and connects the burner pan with it. Air passages (one of which is shown at 18) are 65 located between the arms 16, and admit oxygen through the opening 15, to the space directly above the burner pan.

Resting on the face 13^a of the burner pan bottom is a spreader plate 19, which is of 70 less diameter than the internal diameter of the flange 14, to leave an annular space 20 therebetween, and said spreader plate is formed with lugs 21 arranged circumferentially along the lower face thereof, and 75 spaced apart to leave notches or passages 22 therebetween for the escape of the burning vapor. The lower face 23 of the spreader pan is flat and parallel with the upper face 13^a of the bottom 13 of the spreader 80 pan. I have found from actual experiments that the proper height of the notches or 85 passages 22 is about five sixty-fourths of an inch, to bring about the best results, because if the notches are higher, a roaring sound is produced, and if the notches are lower a choking action results. In order to centralize the spreader plate and space it from the annular flange 14, three or more lugs 21 are extended beyond the plate to 90 the flange, as at 24. To prevent warping of the plate, I prefer to form radially extending ribs 25 on its upper side that extend from a central boss 26 to an annular rib 27, formed on the upper side and at the 95 margin of the spreader plate.

In accordance with the usual practice, a priming cup (not shown) is employed for receiving alcohol or other volatile fluid which is ignited to pre-heat the parts and 100 gasify the kerosene or other liquid fuel in the top of the burner tube. The fuel (under pressure) is then turned on and the gaseous fuel discharged through the duct 11^a in a fine jet or stream against the bottom of 105 the spreader pan where it is spread outwards evenly in all radial directions, passing through the notches 22 and being deflected upward by the annular flange 14. The gaseous fuel is ignited and burns with a 110 blue, intensely hot flame, without producing any appreciable noise or roaring sound,

The heat generated in the burner pan is conducted to the burner tube by the arms 16, and gasifies the liquid fuel in the upper end thereof.

5 From my experiments I found it necessary, in order to obtain the best results, to provide a relatively long, discharge duct in the burner tube of exceedingly small diameter, practically a capillary duct, and located in position so as to direct the fine jet or stream at the center of the spreader plate, in order that the fuel may be spread evenly in all radial directions from the center of the plate. I also find that unless 10 the height of the notches or passages is limited closely to five sixty fourths of an inch, a roaring sound will be produced if the notches are appreciably higher, and a choking action will result if they are made lower. 15 I also find that it is essential that the adjacent faces of the spreader plate and burner pan be made flat and parallel.

20 The burner is capable of use in stoves, heaters, furnaces, and in fact in many other devices where an intensely hot flame is desired. With this burner the fuel is economized and ordinary commercial kerosene may be used effectively as the fuel.

25 More or less variation of the exact details 30 of construction is possible without departing from the spirit of this invention; I desire, therefore, not to limit myself to the exact form of the construction shown and described, but intend, in the following claims 35 to point out all of the invention disclosed herein.

I claim as new, and desire to secure by Letters Patent:

1. A burner comprising, in combination, 40 a burner tube having a thin side wall and a relatively thick top wall, the top wall being formed with a centrally disposed, relatively long, capillary discharge duct, a centrally apertured burner pan secured upon 45 said burner tube, and having an upturned marginal flange, the upper face of said burner pan being flat, and a spreader plate above and spaced relatively close to said burner pan, the spreader plate being of less diameter than the internal diameter of said flange, and its lower face being flat and 50 parallel with the upper flat face of the burner pan, the flat upper face of the burner pan and lower flat face of the spreader plate forming therebetween a relatively thin hori-

zontal passage of uniform thickness throughout and the space between the edge of the spreader plate and flange of the burner pan being relatively wide as compared with the thickness of said flat passage.

2. A burner comprising, in combination, 60 a burner tube having a thin side wall and a relatively thick top wall, the top wall being formed with a centrally disposed, relatively long, capillary discharge duct, a centrally apertured burner pan secured upon 65 said burner tube, and having an upturned marginal flange, the upper face of said burner pan being flat, and a spreader plate above 70 said burner pan, and of less diameter than the internal diameter of said flange, said spreader plate being formed with a row of spaced lugs on its lower face, arranged circumferentially about the same, and resting on the bottom of said spreader pan, the 75 spaces between said lugs being relatively low, the flat upper face of the burner pan and lower flat face of the spreader plate forming therebetween a relatively thin horizontal 80 passage of uniform thickness throughout and the space between the edge of the spreader plate and flange of the burner pan being relatively wide as compared with the thickness of said flat passage.

3. A burner comprising, in combination, 85 a burner tube having a thin side wall and a relatively thick top wall, the top wall being formed with a centrally disposed, relatively long, capillary discharge duct, a centrally apertured burner pan having downwardly 90 converging arms terminating in a band secured upon said burner tube, said burner pan being formed with an upturned marginal flange, and the upper face of the bottom of 95 said burner pan being flat, and a spreader plate above said burner pan and of less diameter than the internal diameter of said flange, the lower face of said spreader plate being flat, and formed with a marginal row 100 of spaced lugs resting on the bottom of the burner pan, the spaces between said lugs being relatively low, the flat upper face of the burner pan and lower flat face of the spreader plate forming therebetween a relatively thin horizontal 105 passage of uniform thickness throughout and the space between the edge of the spreader plate and flange of the burner pan being relatively wide as compared with the thickness of said flat passage.

AXEL WARNER.
